[57] CLAIM

The ornamental design for a display receptacle, as shown and described.

DESCRIPTION

FIG. 1 is a perspective view of a display receptacle showing my new design;

FIG. 2 is a front elevational view of FIG. 1;

FIG. 3 is a top plan view of FIG. 1, the bottom being flat and unornamented;

FIG. 4 is a side elevational view taken from the left of FIG. 1;

FIG. 5 is an elevational view taken in the direction of the rear corner from the right of FIG. 1;

FIG. 6 is a perspective view of a second embodiment of the design of FIG. 1, the only difference being the omission of the upper shelf and the shifting upwardly of the lower shelf.
